COMBINATION AIRPLANE AND AUTOMOBILE

Arne F. Vinje, Santa Monica, Calif.

Application April 5, 1948, Serial No. 145,524

Term of patent 7 years

(Cl. D71—1)

To all whom it may concern:

Be it known that I, Arne F. Vinje, a citizen of the United States, residing at Santa Monica, in the county of Los Angeles and State of California, have invented a new, original, and ornamental Design for a Combination Airplane and Automobile, of which the following is a specification, reference being had to the accompanying drawings, forming part thereof.

Fig. 1 is a top plan view of a combination airplane and automobile, showing my new design;

Fig. 2 is a top perspective view;

Fig. 3 is a top perspective view of the automobile unit; and

Fig. 4 is a top perspective view of the wing and tail section of the design.

I claim:

The ornamental design for a combination airplane and automobile, substantially as shown.

ARNE F. VINJE.
